DISINTEGRATING HEAD FOR CONTINUOUS MINER

Arthur Lee Barrett, Franklin, Pa., assignor to Joy Manufacturing Company, Pittsburgh, Pa., a corporation of Pennsylvania

Application March 30, 1954, Serial No. 419,657

2 Claims. (Cl. 262—26)

This invention relates to a disintegrating head for a continuous miner and more particularly to a disintegrating head of a rotary drum type having paddles secured to the drum for moving the disintegrated mineral rearwardly away from the working face during the mining operation.

An object of this invention is to provide an improved disintegrating head. Another object is to provide an improved rotary toothed drum type disintegrating head for a continuous miner, having improved paddles on the drum for moving the mineral dislodged by the drum-teeth. A further object is to provide an improved rotary drum type disintegrating head having paddles and cutter supports secured in an improved manner to the paddles and to the drum. Another object is to provide an improved paddle and cutter support arrangement for a drum type disintegrating head. These and other objects and advantages of the invention will, however, hereinafter more fully appear in the course of the ensuing description and as more particularly pointed out in the appended claims.

This application is a continuation-in-part of my application Serial No. 320,665, filed November 15, 1952, now matured into Patent No. 2,788,200, patented April 9, 1957.

In the accompanying drawings there are shown for purposes of illustration two forms which the invention may assume in practice.

In these drawings:

Fig. 1 is a fragmentary plan view of a disintegrating head in which a preferred illustrative form of the invention is embodied.

Fig. 2 is an enlarged view in central longitudinal vertical section taken on line 2—2 of Fig. 1.

Fig. 3 is a perspective view of the forward drum portion of the head, with the latter in raised position.

Fig. 4 is an enlarged perspective view of a modified form of disintegrating head, with the head in lowered position.

Fig. 5 is a plan view of the outer drum portion of a disintegrating head shown in Fig. 4.

Figs. 6 and 7 are longitudinal vertical sections taken on lines 6—6 and 7—7 respectively of Fig. 5, illustrating details of the modified drum structure.

As disclosed in my application Serial No. 320,665, above referred to now matured into Patent No. 2,788,200, patented April 9, 1957, the improved disintegrating head, generally designated 1, is shown associated with a continuous miner having a frame 2 on which the disintegrating head is pivotally mounted on a horizontal transverse axis, at 3, to swing in vertical planes relative thereto. The disintegrating head during operation of the miner dislodges and disintegrates the mineral of a solid mine vein and embodies an endless head conveyor 4 for receiving the disintegrated mineral and for moving the disintegrated mineral received thereby rearwardly to discharge onto a conventional rear discharge conveyor 5 which, at its for-

2

ward portion, extends forwardly and downwardly beneath the disintegrating head.

In both illustrative forms of the invention, the disintegrating head includes a swingable frame or guide bar structure 6 having parallel vertical side bars 7 about the margins of which endless side disintegrating chains 8 are guided for orbital circulation, and driven by these side chains and arranged transversely of the head frame between the forward portions of the side bars is a toothed disintegrating drum or bit-carrying roller 9, of an improved design. The parallel side bars of the head frame are suitably rigidly connected by transverse frame portions 10 which provide suitable guideways for the endless head conveyor 4.

Arranged transversely of the frame 2 in coaxial relation with the pivot 3 of the disintegrating head is a drive shaft 11 and secured to this cross shaft (Fig. 2) are chain sprockets 12 which engage and drive the endless side disintegrating chains 8 of the disintegrating head. Also secured to and driven by this cross shaft are sprockets 13 which engage and drive endless side chains 14 of the head conveyor 4, which is of a conventional construction. These conveyor side chains have usual transverse scraper bars or flights 15 secured thereto at intervals along their lengths and these scraper bars are movable over the top surface 16 of the transverse upper portion 10 which extends between and is secured to the vertical side bars of the head frame.

The motor driven means for driving the cross shaft 11 is fully disclosed in my above mentioned application now matured into Patent No. 2,788,200 and since it does not per se enter into the present invention, a disclosure thereof is herein unnecessary, other than to state that the side disintegrating chains, the rotary drum and head conveyor 35 may be driven irrespective of the angular position of the head frame about its pivotal axis relative to the support 2. Any suitable means may be provided for swinging the head frame in vertical planes about its pivot and for holding the head frame in its different angular positions.

Now referring to the detail structure of the improved toothed drum of the preferred embodiment, shown in Figs. 1 to 3 inclusive, it will be noted that the cylindrical body of the drum 9 is composed of semicircular comple-

45 mental parts 17 suitably secured together, as by screws 18, and these drum-parts when rigidly secured together surround and are keyed to a cross shaft 19 suitably journaled within the sides of the forward portion of the head frame. This cross shaft 19 is suitably driven by the side disintegrating chains 8 in a well known manner. The toothed drum extends transversely between the inner

50 sides of the vertical side bars 7 of the head frame and has secured thereto, as by welding or otherwise, a series of blade-like vanes or paddles 20 projecting radially from the drum-body and these paddles serve to convey the disintegrated mineral upwardly and rearwardly to discharge onto the head conveyor 4. Arranged in staggered relation on the drum and secured, as by welding or otherwise, to the rear sides of the paddles 20 and to the drum-body are cutter supports 21 which carry detachable cutting

55 teeth or bits 22 and these drum teeth, during operation of the miner, engage and tear away the solid mineral from the mine vein.

Extending transversely between the vertical side bars of the head frame rearwardly of the drum is a toothed comb or grizzly 23 having teeth 24 separated by vertical arcuate slots 25 through which the drum teeth pass as the drum revolves and this grizzly serves to deflect the disintegrated mineral from the drum and to direct it rearwardly onto the head conveyor 4.

70 In the modified construction, shown in Figs. 4 to 7 inclusive, the swingable frame structure, side chains, the grizzly and the drum or roller are similar to those of

the form above described, and the drum 9' has its cylindrical body peripherally grooved at 26 at spaced points along its length and these grooves are annular and extend circumferentially of the drum. Secured, as by welding or otherwise, to the drum-body are bit supports or lugs 21' having portions 27 projecting within the grooves 26 so that the side walls of the grooves provide rigid lateral supports for teeth or bits 22' secured, as by set screws 28, within suitable sockets in the supports or lugs. The disintegrating teeth are arranged in staggered relation on the drum, as in the preferred form of the invention, and secured, as by welding or otherwise, to the drum-body and to the bit supports or lugs are radial paddles 20'. The bit supports have secured, as by welding or otherwise, to their lugs narrow vertical backing plates 29 which provide abutments at the rear surface of the cutter bits and certain of these plates abut at 30 the adjacent paddles, as shown in Fig. 6. As shown in Fig. 7, certain of the paddles are secured, as by welding, to the backing plates 29, as at 31, while others of the paddles extend between and are secured, as by welding, to the bit lugs, as shown at 32 in Fig. 7. As shown in Fig. 6, certain of the paddles extend between and are secured, as by welding, to the backing plates 29, as shown at 33. The head conveyor 4', in this instance, comprises parallel flight conveyor chains 34, as shown in Fig. 5, and these parallel conveyor chains operate in unison to convey the disintegrated mineral rearwardly along the head frame.

In both forms of the invention the forward surfaces of the grizzly teeth are shaped to clear the drum paddles as the drum is rotated and the grizzly teeth project in adjacency to the paddles so that they tend to deflect the disintegrated mineral as it is discharged rearwardly from the paddles in a rearward direction toward the head conveyor 4. In the form of the invention shown in Fig. 2, five paddles are shown while in the form shown in Figs. 6 and 7, there are but four paddles, although, evidently, the number of the paddles may be varied as desired.

In both forms of the invention the disintegrating head may be swung downwardly about its pivot and when in lowered position may be dumped rectilinearly into the mineral of the mine vein near the floor level and, after dumping, the head may be swung upwardly in vertical planes about its pivot to effect disintegration of the solid mineral between the floor and roof, and finally the head may be retracted from the mine vein at the roof level, all in manners well known to those skilled in the art. As the mineral is dislodged from the mine vein and disintegrated by the disintegrating chains and toothed drum, the disintegrated mineral is received between the paddles of the drum and these paddles throw the disintegrated mineral rearwardly from the drum toward the head conveyor 4 and the latter conveys the disintegrated mineral rearwardly of the head to discharge onto the rear discharge conveyor 5 of the miner.

As a result of this invention an improved disintegrating head is provided for dislodging and disintegrating the mineral of a solid mine vein. By the provision of the improved arrangement of the teeth or cutter bits on the drum or roller and the novel relation of the conveying paddles with respect to the drum-body and the tooth or bit supports, the disintegrated mineral is conveyed rearwardly away from the working face in an improved manner. These and other advantages of the invention will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

- 10 1. A disintegrating head comprising a head frame pivoted to swing vertically, a cylindrical drum having paddlelike mineral conveying vanes each extending longitudinally the length of the drum and extending radially of the drum axis, said vanes on said drum each presenting sufficient mineral engaging vane face for effectively conveying mineral dislodged away to the rear from the mine face, said drum arranged transversely and journaled on the outer portion of the head frame, multiple combination tooth supporting and vane bracing means secured to the drum periphery and to said vanes as by welding, said paddlelike mineral conveying vanes providing transverse support for respective tooth supporting and vane bracing means attached thereto, said tooth supporting and vane bracing means having circumferentially extending webbing with curved inner surfaces fitting against the curved exterior surface of said drum and said tooth supporting and vane bracing means supporting cutting teeth radially outward substantially beyond the cylinder of rotation generated by the radially outward edges of said vanes to the degree necessary for complete mineral dislodgment from the mine face before the mineral comes into conveyable relation with said mineral conveying vanes.
- 15 2. A disintegrating head comprising a head frame pivoted to swing vertically, a cylindrical drum having multiple paddlelike mineral conveying vane means with each said vane means extending longitudinally the length of the drum and extending radially of the drum axis, multiple combination tooth supporting and vane bracing means secured to the drum periphery and to said vane means as by welding, each said vane means presenting a front mineral engaging and conveying face the entire length of said drum except where interrupted by respective said tooth supporting and vane bracing means, each said vane means sufficiently radially extended for effectively engaging and conveying the mineral dislodged away to the rear from the mine face, said tooth supporting and vane bracing means supporting mineral cutting and dislodging teeth radially outward substantially beyond the cylinder of rotation generated by the radially outward edges of said vane means to the degree necessary for complete dislodgment of the mineral from the mine face before the mineral comes into conveying relation with said mineral conveying vane means.
